UNITED STATES PATENT OFFICE.

ARTHUR R. COLLIER, OF NEW SOUTHGATE, ENGLAND.

LOCKING DEVICE.

1,420,910.

Specification of Letters Patent. Patented June 27, 1922.

Application filed May 17, 1920. Serial No. 382,070.

To all whom it may concern:

Be it known that I, ARTHUR REGINALD COLLIER, a subject of the King of Great Britain and Ireland, residing at 64 Brownlow Road, New Southgate, Middlesex, England, have invented new and useful Improvements in and Relating to Locking Devices, of which the following is a specification.

10 My invention relates to a lock, operated from a common centre, for securing a door or the like at three or more places, and designed for use on the outside doors of private houses, flats, shops, warehouses, 15 churches, garages and other places liable to be left at times without an occupant. The invention is also applicable for use on the doors of strong-rooms, store-rooms and the like.

20 Broadly stated the invention comprises a lock for securing a door or the like at three or more points, which when secured by the turning of a handle or knob on the outside of the door can only be operated from the 25 outside by means of a key and cannot be operated from the inside by any means.

According to the invention a horizontal sliding bolt is adapted to normally project in front of the lock case and bevelled or 30 rounded on one side of the projecting end in the form of an ordinary latch bolt. This latch bolt is combined with an inner horizontally sliding member contained entirely within the lock case and two or more vertically sliding bolts respectively adapted to 35 engage when moved to the locking position in staples or boxes arranged in the door frame above and below the door.

The combination of bolts is operated and 40 controlled by a key and inside and outside knobs or handles and is so arranged that by closing the door and turning a knob on the outside of the door, it is secured in three or more places and cannot be opened by any 45 means from inside, and only by the use of the key from the outside. While by closing the door and turning the knob on the inside and by securing the vertical bolts at top and bottom by additional locking means the 50 door is secured in three or more places and cannot be opened from the outside by any means, but can be opened from inside by first releasing the vertical bolts at top and bottom and then turning the knob or handle. 55 When the vertical bolts are drawn and the lock is in normal "on the latch" position,

the door may be freely opened from both inside and outside by turning the knob but the vertical bolts cannot be operated.

The invention is illustrated by way of example in the accompanying drawings, in which—

Figure 1 shows the lock with its parts in the normal "on the latch" position with the vertical bolts drawn. 65

Figure 2 shows the lock with the parts fully bolted.

Figure 3 shows a section on the line A—B of Figure 1 looking in the direction of the arrow. 70

Figure 4 shows a section on the line C—D of Figure 1 looking in the direction of the arrow.

Figure 5 shows the lock with its parts in the withdrawn position (the vertical bolts 75 being removed for sake of clearness).

Figure 6 shows the general arrangement on the inner side of the door.

Figure 7 shows a detail view of the member of the divided handle spindle directly 80 connected with the outside door handle.

Figure 8 shows detail views of the member of the divided handle spindle directly connected with the inside door handle.

Figure 9 shows a perspective view of the 85 parts forming the divided spindle assembled.

Figure 10 shows a detail view of a guide for the vertical bolts and the grooved end of the vertical bolt adapted to be engaged 90 by a hinged member on the guide.

Figure 11 shows an additional locking bolt operated by the vertical bolt.

Figure 12 shows an alternative form of the additional locking bolt. 95

Figure 13 shows an alternative form of horizontal stop.

Figure 14 shows an alternative form of lock in which the latch bolt can be withdrawn by the key through the inner sliding member, and 100

Figure 15 shows an alternative form of the actuating cam on the inside member of the divided spindle.

Referring now to the drawings a pair of 105 vertically sliding bolts 1 (Figure 6) are operated from one or both sides of the door by means of knobs or handles 2 fixed upon a divided spindle (Figure 9) and when shot engage in staples 3 as shown, or boxes or the like fixed on the door frame 4 or in recesses 110 provided in the same. The divided spindle

which is shown in detail in Figures 7 and 8 is employed to allow the inner knob or handle to be turned to a certain distance to draw the latch bolt 5 when the outer knob or handle is locked by cam 6 on its part of the spindle engaging the butt end of a stop 7 and thus preventing further movement of the cam 6 until the stop is lifted, shown in Figure 1. The horizontally sliding latch bolt 5 assumes a latching or half throw position limited by a removable stop 45 or a full thrown or locking position when said stop is removed due to projection by its spring 9 engaging the lug 90 carried by the said bolt 5. Slidably nested on the latch bolt is a plate or inner bolt member 8 carrying a lug 18 and projectable by a spring 10 engaging another lug 100 carried by the said member 8 to move the lug 18 into a notch 19 in vertical bolt 1 when said bolt is moved to locking position to bring notch 19 in registration with lug 18. The inner bolt member 8 is operated by means of a suitable key spindle 11 fitted with suitable operating means such as cams 12 (as shown), cogs, spokes or the like engaging with corresponding cam members 13 projecting from the wall of a central recess 14 in the said sliding member 8. This key spindle 11 is adapted to be turned from the outside of the door by the key only. The key operated gear itself forms no part of this invention and may be of any suitable form convenient for the thickness of the door on which the lock is mounted. The portion of the divided spindle (Figure 7) connected directly with the outside handle operating the vertically sliding bolt 1 is fitted with cams 15 as shown, or cogs, spokes or the like, so arranged that when the spindle is turned by a knob or handle from the inside or outside of the door the cam members 15 engage in correspondingly shaped recesses 16 on the sides of the vertical bolts, and cause said bolts to travel in opposite directions. As shown in Figure 3 one of these vertically sliding bolts 1 is so formed that when in the withdrawn position a shoulder 17 thereon engages with a shoulder 18, Figure 5, on the key operated horizontally sliding member 8 and holds the latter in position against its spring 10. Upon turning the outer handle or knob in order to shoot the vertical bolts, the bolt 1 with the shoulder 17 travels to a position in which a recess 19 therein is in alignment with the shoulder 18 of the key operated sliding member 8 thus allowing the same to move forward under the influence of its spring 10 and its shoulder 18 to pass into said recess 19 and to hold the vertical bolt 1 firmly locked against operation by the cams 15 mounted on the divided handle spindle. When the bolts 1 are thus shot the door is secured at the top and bottom and at the side by the latch bolt 5 and can only be opened by the use of a key from the outside to turn the spindle 11 through which the sliding member 8 can be withdrawn to a position in which the shoulder 18 is clear of the recess 19 in the upper vertical bolt. The channel 40 above the shoulder 17 in the bolt 1 receives the flange 41 of the latch bolt 5, (Figures 1 and 3). This flange 41 normally rests in this channel when the latch bolt is in the "on the latch" position and so prevents the bolts 1 from being shot until the sleeve portion of a spring controlled vertical stop 24 has been withdrawn from the latch bolt 5 on the inside of the door by the person opening the door through an actuating arm 42 outside the lock casing. The crank projection 6 on the portion directly connected with the outside handle of the divided spindle engages in the V between the members 20 and 21 of the inside portion as shown in Figure 9. These members 20, 21 are arranged so far apart that when the spindle connected with the outside handle has been revolved beyond the point necessary to withdraw the vertical bolts 1 the inside part of the spindle (Figure 8) can still be turned a sufficient distance in said V for its cam member 22 to engage the end of the lever arm 23 which is in alignment with the sliding latch bolt 5 and to withdraw the same against the influence of the spring 9 to a position in which it is clear of the box on the door frame. When the outside handle is turned to withdraw the bolts the projection 6 on the outside part of the spindle is adapted to lift the vertical spring controlled stop 45 into engagement in recess 25 in the sliding member 8 and the latch bolt and thus holds both in their normal positions in the lock casing, with their springs 9 and 10 partially compressed. This double stop formed by the pin 24 and sleeve 45, and the crank 6, is further controlled by an outdoor latch stop 7 best seen in Figure 4. The stop slides in a boss 48; it has a head 27 by which it may be withdrawn from inside the door against the action of a spring 49 compressed between the end of the boss and the transverse pin 50 in the stop; this pin further engages a groove 51, shown as a spiral groove in Figure 4, and so serves to retain the stop in inoperative position against the action of the spring. The action of the apparatus may be seen from Figures 1, 2 and 5. In Figure 1 the parts are shown in the "indoor latch" position. The bolts 1 are withdrawn, the flange 41 is engaged in the recess 40 of the upper bolt and so prevents the bolts being shot. If either handle is turned the latch cam 22 will rotate the lever 23 and partially withdraw the latch bolt 5. Before it is fully withdrawn the crank 6 abuts upon the out-door latch stop 7 and the

outdoor handle can be no further turned; hence the door cannot be opened from outside. But on account of the lost motion between the crank 6 and the V 20, 21, the indoor handle can be turned a little further, sufficiently to withdraw the latch bolt 5 wholly from its socket.

If the stop 7 is withdrawn by rotating the head 27 there is no obstacle to movement of the cam 6 except the offset portion of the stop 24; moreover, this stop can be lifted by the crank against the action of spring 46. In this condition, therefore, the latch can be withdrawn from indoors or outdoors.

If the parts are in the indoor latch position and the occupant proposes to leave the house for some time, and desires to leave it safely locked, his first action is to pull down the fingerpiece 42, so withdrawing the latch bolt stop 45 from the slot 255. The spring 9 being already in compression will thrust forward the latch bolt 5 sufficiently to carry the flange 41 out of the slot 40 of bolt 1. The bolts are then free to be shot. Next the stop 7 is withdrawn; the compressed spring 46 at once thrusts down the stop 24, so withdrawing it from the recess 25 in the member 8. The occupant then leaves the house, closes the door and shoots the bolts 1, by rotating the outdoor handle. As soon as the recess 19 in the upper bolt comes opposite the shoulder 18 of the member 8 the member will move forward under the action of its spring 10 and engage the shoulder in the recess. Thus the bolts are locked in shot position. This "occupant absent" condition is shown in Figure 2. The door cannot now be opened from inside at all, and can only be opened from outside by the use of the proper key. To open it the spindle 11 is turned by the aid of the key, so that the cams or lugs 12 withdraw the member 8 against the action of spring 10. When it has moved so far that the shoulder 18 is clear of the upper bolt the two vertical bolts can be withdrawn by rotating the outdoor handle. At the end of this motion the cam 22 engages the lever 23 and withdraws the latch. There is no obstacle to the passage of crank 6 except the offset part of the stop 24; and since member 8 has been withdrawn so that its recess 25 is vertically over the stop 24 the crank 6 can lift the stop against the action of its spring 46.

If the occupant is indoors but desires to lock up the house securely for the night he releases the latch bolt stop 45, as before, and shoots the bolts 1 by means of the indoor handle. As a final security to prevent the bolts being withdrawn from outdoors he engages the hinged members 30 with the slots 31 in the bolts. This is the "occupant within" condition. In Figure 15 I show an alternative form of the cam 6 which enables the outside handle to be locked from movement

in either direction by means of the stop 7. In this form a curved recess 43 is provided in the engaging face of the cam 6 adapted to receive the stop 7. This curved recess 43 is deep enough for its extremity 44 to engage the stop 7 and to prevent the outside handle from being turned in either direction when the stop is in position in said recess. The stop 7 can be put out of action to enable the door to be opened by the outside handle from the "on the latch" position. Any suitable means may be employed to retain this stop 7 in the free position out of action such for instance, as shown in Figure 13, in which a lateral pin 28 can be arranged to engage in a bayonet channel cut in the wall of the sleeve 29 enclosing the stop and operating spring. When the door is bolted from the inside, the vertical bolt can be further secured at the top and bottom of the door by a hinged member 30 on the bracket 32 adapted to engage in one or other of the recesses 31 at the extremities of the bolts 1. The bracket 32 is fixed in a suitable position to the face of the door and the member 30 is adapted to engage the upper recess 31 when the bolt is in the withdrawn position and the lower recess when the bolt has been shot. Any equivalent device can be used.

In Figure 14 I show an alternative form of lock for use in premises such as dwelling houses in which it is convenient to allow of the inner sliding member 8 having a longer rearward travel the recess 25 and slot 255 being elongated for this purpose, so as to admit of the complete withdrawal of the latch bolt 5 by the key alone when the latter is in the "on the latch" or normal position. This arrangement allows of the house being entered by more than one person provided with duplicate keys. In Figures 11 and 12 I show by way of example two methods of securing a door at more than three places. In Figure 11 I show two views in which one or more additional sliding bolts 35 are slidingly fixed on the side of the door and are operated by the curved part 36 of the vertical bolt 1 which curved part operates said bolt 35 through the pins 37. In the upper figure the bolt 35 is shown withdrawn while in the lower figure it is shown in engagement with the staple 38 on the door frame. In the alternative form shown in Figure 12 the bolts 35 are pivoted to the vertical bolts 1 and to the door at 39 so that as said bolts 1 rise and fall the bolts 36 are shot or withdrawn signal fashion.

What I claim is:—

1. A lock operated from a common centre for securing a door at a plurality of places comprising a casing, a latch bolt sliding within said casing, vertical bolts, a handle operating said bolts, a key operated member actuating said latch bolt, and means

controlling said latch bolt adapted to be released by the action of the person securing the door to move said member and latch bolt forward automatically when said vertical bolts are moved to their shot position.

5 2. A lock operated from a common centre for securing a door at a plurality of places comprising a casing, a latch bolt sliding within said casing, vertical bolts, a handle 10 operating said bolts, a key operated member sliding in a recess in said latch bolt, means controlling said member adapted to be released by the action of the person securing the door to move said member and 15 latch bolt forward automatically when said vertical bolts are moved to their shot position.

3. A lock operated from a common centre for securing a door at a plurality of places 20 comprising a casing, a latch bolt sliding within said casing, vertical bolts, a handle operating said vertical bolts, a key operated member sliding in a recess in said latch bolt, a spring pressing said member, a double 25 stop adapted to hold said latch bolt and key operated sliding member in the respective "on the latch" positions and which admits of the latch bolt being released at will by the person securing or fastening the door 30 and the sliding member being released by the further deliberate action of the person securing or fastening the door.

4. A lock operated from a common centre for securing a door at a plurality of places 35 comprising a casing, a latch bolt sliding within said casing, vertical bolts, handles operating said bolts from both sides of the door, a divided spindle carrying said operating handles, means connecting the adjacent ends of said spindle parts in such a manner as to allow the inner handle to be turned to draw the latch bolt when the outer handle is locked, a key operated member sliding in a recess in said latch bolt, 45 a spring pressing said member adapted to move the said member and latch bolt forward automatically when said vertical bolts are moved to their shot position.

5. A lock operated from a common centre 50 for securing a door at a plurality of places comprising a casing, a latch bolt sliding within said casing, vertical bolts, handles operating said bolts from both sides of the door, a divided spindle carrying said operating handles, a stop crank carried at the end of one part of the spindle, a V cam carried by the adjacent end of the other part of the divided spindle in which the said stop crank engages in such a manner as to 55 allow the inner handle to be turned to draw the latch bolt when the outer handle is locked, a key operated member sliding in a recess in said latch bolt, a spring pressing said member adapted to move the member 60 and latch bolt forward automatically when 65

said vertical bolts are moved to their shot position.

6. A lock operated from a common centre for securing a door at a plurality of places comprising a casing, a latch bolt sliding 70 within said casing, vertical bolts, a handle operating said bolts, a member sliding in a recess in said latch bolt, a series of cams projecting from said member, an operating spindle, a series of cams on said spindle engaging with the corresponding cams projecting from said sliding member, a spring pressing said member adapted to move the said member and latch bolt forward automatically when said vertical bolts are moved to their shot position.

7. A lock operated from a common centre for securing a door at a plurality of places comprising a casing, a latch bolt sliding within said casing, vertical bolts, a handle 85 operating said bolts, a shoulder on the latch bolt adapted to engage in a recess in one of the vertical bolts to prevent said vertical bolts from being operated from inside or outside when the latch is in the normal "on the latch" position, a key operated member sliding in a recess in said latch bolts, a spring pressing said member adapted to move the said member and latch bolt forward automatically when said vertical bolts are moved to their shot position.

8. A lock operated from a common centre for securing a door at a plurality of places comprising a casing, a latch bolt sliding within said casing, vertical bolts, a handle 100 operating said bolts, a shoulder on the latch bolts adapted to engage in a recess in one of the vertical bolts to prevent said vertical bolts from being operated from inside or outside when the latch is in the normal "on the latch" position, a key operated member sliding in a recess in said latch bolts, a rib on one of said vertical bolts, a spring pressing said member adapted to move said member and latch bolt forward automatically 105 when said vertical bolts are moved to their shot position and a shoulder on said sliding member adapted to engage with the rib on the vertical bolt when the bolt is drawn and to hold said member against the influence of 110 its spring.

9. A lock operated from a common centre for securing a door at a plurality of places comprising a casing, a latch bolt sliding within said casing, vertical bolts, handles 115 operating said bolts from both sides of the door, a divided spindle carrying said operating handles, a stop crank carried at the end of one part of the spindle, a V cam carried by the adjacent end of the other part 120 of the divided spindle in which the said stop crank engages in such a manner as to allow the inner handle to be turned to draw the latch bolt when the outer handle is locked, a key operated member sliding in a recess 125

- in said latch bolt, a spring pressing said member adapted to move the said member and latch bolt forward automatically when said vertical bolts are moved to their shot 5 position, a vertical stop adapted to be lifted by the stop crank on the divided spindle into a recess in the latch bolt and sliding member to hold the latch bolt in its "on the latch" position and the member in the rearmost position in the latch case when the vertical 10 bolts have been withdrawn and a spring controlling said stop.
10. A lock operated from a common centre for securing a door at a plurality of 15 places comprising a casing, a latch bolt sliding within said casing, vertical bolts, handles operating said bolts from both sides of the door, a divided spindle carrying said operating handles, a stop crank provided 20 with a curved recess carried at the end of one part of the spindle, a V cam carried by the adjacent end of the other part of the divided spindle in which the said stop crank engages in such a manner as to allow of 25 the inner handle to be turned to draw the latch bolt when the outer handle is locked, a key operated member sliding in a recess in said latch bolt, a spring pressing said member adapted to move the said member 30 and latch bolt forward automatically when said vertical bolts are moved to their shot position, a vertical stop adapted to be lifted by the stop crank on the divided spindle into a recess in the latch bolt and sliding 35 member to hold the latch bolt in its "on the latch" position and the member in the rearmost position in the latch case when the vertical bolts have been withdrawn, a spring controlling said stop, a horizontal stop 40 mounted in the casing and adapted to engage in the curved recess in the stop crank to lock said crank and the outer handle against rotation.
11. A lock operated from a common centre for securing a door at a plurality of 45 places comprising a casing, a latch bolt sliding within said casing, vertical bolts, hinged members mounted on brackets fixed to the door adapted to engage in one or other of 50 two recesses near the extremities of said vertical bolts which recesses are arranged at such a distance apart that said hinged members engage the upper recesses when the bolts are in the withdrawn position and the 55 lower recesses when the bolts have been shot, a spindle operating said bolts, a key operated member sliding in a recess in said latch bolt, a spring pressing said member adapted to move the said member and latch bolt forward automatically when said vertical bolts are moved to their shot position.
12. A lock operated from a common centre for securing a door at a plurality of 60 places comprising a casing, a latch bolt sliding within said casing, vertical bolts, 65
- catches on the door frame, horizontal sliding bolts registering with said catches and adapted to be operated by said vertical sliding bolts to engage in said catches when the vertical bolts have been shot, a handle operating said bolts, a key operated member sliding in a recess in said latch bolt, a spring pressing said member adapted to move the said member and latch bolt forward automatically when said vertical bolts are moved to their shot position.
13. A lock operated from a common centre for securing a door at a plurality of places comprising a casing, a latch bolt sliding within said casing, vertical bolts, a spring 80 pressing said latch bolt adapted to move the said member and latch bolt forward automatically when said vertical bolts are moved to their shot position, a key operated member sliding in a recess in said latch bolt, 85 handles operating said bolts from sides of the door, a divided spindle carrying said operating handles, a stop crank provided with a curved recess carried at the end of one part of the spindle, a V cam carried by 90 the adjacent end of the other part of the divided spindle in which the said stop crank engages, a series of cams projecting from said sliding member, an operating spindle a series of cams on said spindle engaging with 95 the corresponding cams projecting from said sliding member, a shoulder on the latch bolt adapted to engage in a recess in one of the vertical bolts to prevent said vertical bolts from being operated from inside or outside 100 when the latch is in the normal "on the latch" position, a rib on one of the said vertical bolts, a shoulder on said sliding member, adapted to engage with the rib on the vertical bolt when the bolt is drawn and to hold 105 said member against the influence of its spring, a vertical stop adapted to be lifted by the stop crank on the divided spindle into a recess in the latch bolt and sliding member to hold the latch bolt in its "on the latch" 110 position and the member in the rearmost position in the latchcase when the vertical bolts have been withdrawn, a spring controlling said stop, a horizontal stop mounted in the casing and adapted to engage in said curved 115 recess in the stop crank to lock said crank and the outer handle against rotation, hinged members mounted on brackets fixed to the door adapted to engage in one or other of two recesses near the extremities of said 120 vertical bolts arranged at such a distance apart that the hinged members engage the upper recesses when the bolts are in the withdrawn position and the lower recesses when the bolts have been shot catches on the door frame, horizontal sliding bolts registering with said catches and adapted to be operated by said vertical sliding bolts to engage in said catches when the vertical bolts have been 125 shot.

14. A lock operated from a common centre for securing a door at a plurality of places comprising a casing, a latch bolt sliding within said casing, vertical bolts, a handle operating said bolts, a key operated member adapted to be actuated by the key to withdraw said latch bolt from its latch box when the latter is in the "on the latch" position, and means controlling said latch bolt

adapted to be released by the action of the person securing the door to move said member and latch bolt forward automatically when said vertical bolts are moved to their shot position.

In testimony whereof I have signed my name to this specification.

A. R. COLLIER.
